[57] **CLAIM**

The ornamental design for an combined top sender and bearing plate for an anemometer, as shown.

DESCRIPTION

FIG. 1 is an isometric view of a combined top sender and bearing plate for an anemometer showing my new design;

FIG. 2 is a bottom plan view thereof;

FIG. 3 is a vertical cross-section taken along lines 3—3 of FIG. 2.

FIG. 4 is an exploded side elevational view thereof;
FIG. 5 is a bottom plan view of the top sender taken along lines 5—5 of FIG. 4.

FIG. 6 is a top plan view of the bearing plate taken along lines 6—6 of FIG. 4.

FIG. 1**FIG. 4****FIG. 2****FIG. 5****FIG. 3****FIG. 6**
